MASS SPECTROMETRY

Robert V. Langmuir, Altadena, Calif., assignor, by mesne assignments, to Consolidated Electrodynamics Corporation, Pasadena, Calif., a corporation of California

Application February 8, 1954, Serial No. 408,879

3 Claims. (Cl. 250—41.9)

This invention relates to mass spectrometry and more particularly to an improved instrument of the type generally referred to as a "time of flight" mass spectrometer.

A mass spectrometer is an analytical instrument which functions to ionize a sample to be analyzed, to spatially separate these ions in accordance with their mass-to-charge ratio and to selectively sense the relative abundance of ions of one or more given mass-to-charge ratios. Mass spectrometers operable in this manner take many forms.

One type of instrument of rather recent development is the time of flight mass spectrometer. Instruments of this type as described in the art generally comprise an ion source, a drift tube and a collector electrode. Means are provided in the ion source to project ions into and through the drift tube in mass pulses whereby ions of differing mass segregate themselves in the drift tube into spatially separated ion bunches with each bunch comprising ions of a given mass-to-charge ratio and differing from the mass of ions forming the other bunches. These ion bunches strike and discharge at the collector electrode.

One conventional way of resolving the ion bunches is to gate the amplification and sensing system connected to the collector electrode so that it becomes sensitive only to pulses formed by the successive discharge of ion bunches of a given specific mass. This can be done by interconnecting the pulsing means by which the ions are projected from the ion source and the amplification and sensing system of the collector electrode to determine the proper time sequence of sensitivity of the collector system. A second means of resolving the discharges of the collector electrode is by feeding the amplified output of the collector electrode to a conventional cathode ray tube and adjusting the sweep of the tube so that only the output pulses developed by successive discharge of ion bunches of a given specific mass are displayed on the screen of the tube.

I have now found that instruments of this type are substantially and adversely affected by induced currents developed at the collector electrode responsive to the approach of charged particles. By reason of the presence of a large number of ion bunches of different mass in the drift tube, the resultant induced current in the collector electrode is not a true indication of relative abundance of the ions in any one bunch. The present invention is directed to improvements in a mass spectrometer of this type whereby this problem of induced currents is overcome. To this end the invention contemplates in a mass spectrometer the combination comprising an evacuable envelope, an ion source, means associated with the ion source for propelling ions from the source in mass pulses, a collector electrode disposed in the envelope at a distance from the source and in the path of ions propelled from the source, means operatively associated with the collector electrode to permit resolution of ion masses discharged at the collector electrode,

2

and an electrostatic shield disposed closely adjacent the collector electrode.

The invention will be clearly understood with reference to the following detailed description taken in conjunction with the accompanying drawing, in which:

Fig. 1 is a diagrammatic illustration of a mass spectrometer in accordance with the invention;

Fig. 2 is a diagram of a simple electrostatic circuit illustrating the problem to which the invention is directed;

Fig. 3 is a graph of current flow with time in the electrostatic circuit of Fig. 2;

Fig. 4 shows the mass spectrometer of Fig. 1 provided with a cathode ray display means and without the gating circuit;

Fig. 5 shows a type of signal which may be obtained on a cathode ray display means without the electrostatic shield of the invention; and

Fig. 6 shows the type of signal produced on a cathode ray tube by the illustrated mass spectrometer provided with the electrostatic shield.

Referring first to Fig. 2, the circuit there shown comprises a battery 10 connected between electrostatic plates 11 and 12. A charged particle 13 is shown in the region between the plates 11 and 12 and, as indicated by the accompanying arrow, is considered to be in motion toward plate 12. To move the particle 13 a distance x in time t the rate of work W done by the battery 10 is given by the expression

$$W = iV \quad (1)$$

where

W =work done by battery;

V =the voltage between the plates 11 and 12; and

i =the current flow in the circuit.

The rate of work done on the particle is given by the expression

$$(V/d)(dx/dt)q = (Vv/d)q \quad (2)$$

where

v =the velocity of the particle;

d =distance between the plates (in cm.);

x =a linear coordinate measured between plates 11 and 12;

t =the time coordinate; and

V =the voltage between the plates.

Equations 1 and 2 above must be equal so that

$$i = qv/d \quad (3)$$

where

$$v = dx/dt$$

This current i as given by Equation 3 actually flows in the circuit while the particle is crossing the gap. This current flow is a result of the induced charges on the two plates, which change with time as the particle moves across the intervening region. The shape of the current pulse in this simple example can be shown to be as illustrated in Fig. 3, i. e. substantially triangular because of the uniform increase in velocity as the particle traverses the gap. This subject is discussed in detail in Vacuum Tubes, K. R. Spangenberg, McGraw-Hill, 1948.

The foregoing description illustrates the problem encountered in a time of flight mass spectrometer. Thus, a sharply defined bunch of charged particles will not give a sharp current pulse on arrival at the collector electrode. This effect will be appreciated with reference to the following description of a mass spectrometer in accordance with the invention as illustrated diagrammatically in Fig. 1. The description is based upon the motion and detection of positive ions. Obvious variations in potentials

within the instrument will permit operation with negative ions.

The mass spectrometer of Fig. 1 comprises an evacuable envelope 14 which is shown only schematically in dotted lines since the construction of the envelope and the usual evacuating and sample inlet conduits are unimportant to an understanding of the present invention. An ion source is disposed adjacent one end of the envelope and includes a conventional electron gun 15 for directing an electron beam 16 transversely of the ion source region to an electron target 17. A number of electrodes 18, 19 and 20 are disposed serially in the tube with the electrodes 18 and 19 being oriented on opposite sides of the electron beam 16. A collector electrode 21 is disposed adjacent the opposite end of the tube. In accordance with the present invention an electrostatic shield 22 is disposed immediately in front of the collector electrode 21 and, as illustrated, is biased with a battery 23.

The external circuitry of the instrument is shown diagrammatically as comprising a variable frequency oscillator 24, a pulse former 25 and a high voltage power supply 26 connected serially, with the output of the high voltage power supply being connected across a voltage divider 27. The ion source electrodes 18, 19 and 20 are connected to the voltage divider 27 so that a pulsed accelerating potential is applied to these electrodes whereby ions are propelled from the source in mass pulses in synchronism with the applied pulse.

The variable frequency oscillator 24 is connected through a delay line 28 and a second pulse former 29 to deliver a gating signal to a gated amplifier 31. Collector electrode 21 is connected to the amplifier 31, the output of the amplifier being connected to a conventional sensing system (not shown). The purpose of gating amplifier 31 by means of the oscillator 24, delay line 28 and pulse former 29 is to match the amplifier with the ion accelerating circuit so that the amplifier is sensitive only during the intervals necessary to pick up successive bunches of ions of a given mass.

Ions propelled from the ion source in mass pulses segregate in the drift tube, this being the region between the source and the collector electrode into spatially separated bunches, each bunch consisting of ions of a given mass and there being the same number of bunches as there are ion masses in the ionized sample. Each burst of ions from the ion source results, therefore, in the successive discharge at the collector electrode of ion bunches of each mass represented in the sample. If a particular ion mass is of interest a bunch of ions of this mass will strike the collector electrode for each burst of ions from the ion source but between the arrival of successive bunches of a given mass the collector electrode is also receptive to all of the other ion bunches. To resolve the given mass, energization of amplifier 31 is matched through the described circuit with the pulsed operation of the ion source so that the amplifier is rendered sensitive only in those intervals at which successive bunches of the ion mass of interest strike the collector.

Delay line 28 causes the periods of amplifier energization to lag behind the pulses applied to the ion source by an interval sufficient to allow travel of the ion bunch of the desired mass to the collector.

Resolution of ion masses in this type of an instrument is exceedingly difficult if the electrostatic shield 22 is absent. The reason for this difficulty is made apparent in the discussion of Figs. 2 and 3. The movement of ions in the drift tube of the spectrometer induces a current in collector electrode which increases in magnitude as the ions approach this electrode. Because of the fact that there are a number of ion bunches traversing the drift tube at a given time, this induced current is often unresolvable. I have found that collector electrode 21 can be conveniently masked from the effects of such induced currents by means of the shield electrode 22 disposed

immediately adjacent thereto. If the shield is kept at approximately the same potential as the collector electrode the current induced by the movement of charged particles in the drift tube is absorbed in effect by the mask, and the induced current on the collector electrode will be extremely small until a particular bunch traverses the shield 22. Immediately upon traversal of the shield an ion pulse will induce a large and sharp current in the collector as it traverses the narrow region between the shield and the collector. For this reason it is desirable that the shield be spaced from the collector a distance less than the spatial separation between adjacent ion bunches. A spacing of approximately .005 of an inch is satisfactory for this purpose and is practical from a fabrication standpoint.

The mass spectrometer of Fig. 1 is shown diagrammatically in Fig. 4 connected to a cathode ray tube display system. Like reference characters are used in Fig. 4 to designate elements common to Figs. 1 and 4. In the apparatus of Fig. 4, collector electrode 21 is connected directly through an amplifier 32 to one set of deflecting plates of a cathode ray tube 40. The illustrated connection shows the output of amplifier 32 connected across the vertical deflection plates of the cathode ray tube. The horizontal deflection plates are connected across pulse former 29 so that the horizontal sweep of the tube is matched with the pulsed acceleration from the ion source. A sequence of ion bunches A, B, C and D is shown in its approach to the collector electrode.

Without the electrostatic shield 22, these ion bunches will produce at collector electrode 21 a signal which, when displayed on a cathode ray tube, constitutes the aggregate of the several signals A, B, C and D in the drawing. For purposes of illustration it is assumed that ion bunches A, B, C and D are all present in the same proportions, which causes the respectively developed discharge currents to be of the same magnitude.

In Fig. 5, the net apparent display on the tube is shown as curve 33 which is produced by the multiplicity of signals received by the tube from the collector electrode and as illustrated in dotted lines on the drawing. This gives an appreciation of the difficulties caused by induced current on the collector in the absence of the electrostatic shield 22. The actual current signal on the tube (curve 33) is the sum of the illustrated component signals.

Fig. 6 is another view of a cathode ray tube showing by curve 34 the type of signal obtained in the apparatus of Fig. 4 in the presence of the electrostatic shield 22. By eliminating overlapping induced currents, the shield permits display of a resolved signal as displayed in Fig. 6 wherein the individual peaks produced by discharge of successive ion masses on the collector electrode are observed separately.

I claim:

1. In a mass spectrometer the combination comprising an evacuable envelope, an ion source, a collector electrode disposed in the envelope and spaced from the ion source, means associated with the ion source for propelling ions from the source toward the collector electrode in mass pulses, means operatively associated with the collector electrode to sense ion masses discharged at the collector electrode, and an electrostatic shield disposed adjacent the face of the collector electrode at a distance therefrom, not in excess of the approximate spacing of adjacent ion masses in the region of the shield.

2. In a mass spectrometer the combination comprising an evacuable envelope, an ion source, a collector electrode disposed in the envelope and spaced from the ion source, means associated with the ion source for propelling ions from the source toward the collector electrode in mass pulses, means operatively associated with the collector electrode to sense ion masses discharged at the collector electrode, an electrostatic shield disposed ad-

5 jacent the face of the collector electrode and spaced therefrom such that at no time shall more than one mass pulse have a capacity coefficient to the collector substantially greater than zero, and means for maintaining the electrostatic shield at substantially the potential of the collector electrode.

3. In a mass spectrometer the combination comprising an evacuable envelope, an ion source, a collector electrode disposed in the envelope and spaced from the ion source, means associated with the ion source for propelling ions from the source toward the collector electrode in mass pulses, means operatively associated with the collector electrode to sense ion masses discharged at

the collector electrode, an electrostatic shield disposed adjacent the face of the collector electrode and spaced therefrom such that at no time shall more than one mass pulse have a capacity coefficient to the collector substantially greater than zero, and means for maintaining the electrostatic shield at a potential which is negative with respect to the potential of the collector.
